UNITED STATES PATENT OFFICE.

WENDELIN FAULSTICH, OF BELLEVILLE, ILLINOIS, ASSIGNOR TO BERNARD FAULSTICH AND FREDERICK DAAB, OF SAME PLACE.

CHIMNEY-TOP.

SPECIFICATION forming part of Letters Patent No. 627,775, dated June 27, 1899.

Application filed January 3, 1899. Serial No. 700,883. (No model.)

To all whom it may concern:

Be it known that I, WENDELIN FAULSTICH, a citizen of the United States, residing at Belleville, in the county of St. Clair, State of Illinois, have invented a new and useful Improvement in Chimney-Tops, which improvement is fully set forth in the following specification and accompanying drawings.

My invention consists of a chimney-top constructed to shed water deposited thereon, whether rain, melted snow, or ice, and prevent the same from lodging on or running down the sides or walls of a chimney, as will be hereinafter set forth.

Figure 1 represents a perspective view of a chimney-top embodying my invention. Fig. 2 represents a vertical section thereof on line xx , Fig. 1. Fig. 3 represents a top view of a portion thereof.

Similar letters of reference indicate corresponding parts in the drawings.

Referring to the drawings, A designates a chimney-top consisting of the ledge B, the rim C, and the spout D, the latter extending outwardly from openings in said rim, so as to be in communication with said ledge, and said rim projecting partly above and partly below said ledge, the upwardly-projecting portion forming, with the ledge, a gutter which leads to said spout D and the downwardly-projecting portion surrounding the exterior of the upper portion of the chimney, to which the top is applied. The ledge extends around the tops of the sides or walls of the chimney, so as to allow the products of combustion to escape from the chimney, as usual, and the upper faces of the ledge are inclined downwardly in lateral directions and may also be

inclined toward the spout D, whereby rain or water from melted snow or ice reaches said spout and is discharged by the same beyond the vertical sides of the rim, and consequently of the chimney, and so prevented from lodging on or running down the exterior of the chimney, the same being true of the interior of the chimney.

If desired, discharge-spouts may be applied to the other corners of the top or the sides between the corners, as shown in dotted lines, so as to provide numerous places for shedding the water instead of the single place shown in full lines in the drawings.

The corners of the rim C are prolonged downwardly, as at E, so that they may embrace a number of courses of the masonry, and thus increase the durability of the chimney by preventing its spreading and opening at the joints thereof.

Having thus described my invention, what I claim as new, and desire to secure by Letters Patent, is—

1. A chimney-top consisting of an inclined guttered ledge, a rim extending upwardly and downwardly from the outer end of said ledge and a spout communicating with said ledge and projecting out beyond the outer sides of said rim.

2. A chimney-top consisting of a guttered ledge, a depending rim, a spout and downward prolongations of the corners of said ledge.

WENDELIN FAULSTICH.
